UNITED STATES PATENT OFFICE.

THEODORE PETERS AND ALBERT F. SONDERMANN, OF FERDINAND, INDIANA,
ASSIGNORS TO THE PET-SON PUMP COMPANY, OF FERDINAND, INDIANA, A
CORPORATION OF INDIANA.

VENDING-MACHINE FOR LIQUIDS AND FLUIDS.

1,279,581.

Specification of Letters Patent. Patented Sept. 24, 1918.

Application filed July 7, 1917. Serial No. 179,180.

To all whom it may concern:

Be it known that we, THEODORE PETERS and ALBERT F. SONDERMANN, citizens of the United States, residing in the town of Ferdinand, county of Dubois, and State of Indiana, have invented a certain new and useful Improvement in Vending-Machines for Liquids and Fluids, of which the following is a full, clear, and exact description, such as will enable others skilled in the art to which it appertains to make and use the same.

This invention relates to vending machines of the type that are used for dispensing liquids and fluids.

One object of the invention is to provide a practicable vending machine of simple design and rigid construction that is particularly adapted to be used for dispensing gasoline and oil to automobilists, but which is capable of being used for dispensing various other liquids and fluids.

Another object is to provide a coin-controlled vending machine for liquids and fluids in which the means that governs the quantity of the commodity discharged from the machine is of novel construction and so designed that it can be changed or modified easily whenever the market price of the commodity being vended changes, thereby making the machine particularly adaptable for vending a commodity whose market price fluctuates. Other objects and desirable features of my invention will be hereinafter pointed out.

To this end we have devised a machine for vending liquids and fluids that comprises a meter, a discharge valve that is adapted to be opened so as to cause the commodity being vended to pass through the meter and operate same and thereafter be discharged from the machine, an actuating mechanism for said discharge valve that is normally locked so as to hold the discharge valve closed and a controlling mechanism governed by the meter for causing the discharge valve to close automatically after a certain quantity of the commodity being vended has been discharged from the machine. The machine is preferably provided with a coin-controlled device for locking the valve actuating mechanism, and the controlling mechanism governed by the meter

is so constructed that the discharge valve will close after the machine has delivered a 55 quantity of the commodity equal in value to the value of the coin that was introduced into the machine prior to the opening of the discharge valve. In order that the machine may be used for dispensing a commodity 60 whose market price changes frequently, we have provided the controlling mechanism above referred to with a removable member equipped with spaced elements that govern the closing of the discharge valve, which 65 member is adapted to be replaced by a member provided with differently spaced elements whenever the market price of the commodity being vended changes.

Figure 1 of the drawings is a side elevational view of a vending machine constructed in accordance with our invention.

Fig. 2 is a top plan view of said machine.

Fig. 3 is a front elevational view.

Fig. 4 is a rear elevational view.

Fig. 5 is a side elevational view similar to Fig. 1, but showing the opposite side of the machine.

Fig. 6 is a detail sectional view, illustrating certain parts of the valve actuating 80 mechanism.

Fig. 7 is a sectional view, taken on the line 7—7 of Fig. 6; and

Fig. 8 is a side elevational view, illustrating a machine provided with an electrically operated device, in addition to the coin-controlled device, for effecting the release of the valve-actuating mechanism.

Referring to the drawings which illustrate the preferred form of our invention, A designates a liquid or fluid meter of any preferred type, B designates a supply pipe that leads to a supply of liquid under pressure, and C designates a discharge pipe that is equipped with a valve D that governs the discharge of the commodity from the machine. The machine is adapted to be used for dispensing either a liquid or fluid, but for the sake of brevity, we will hereinafter use the term "liquid" in referring to the commodity dispensed by the machine. If the machine is to be used for dispensing gasoline, oil and various other liquids in relatively large quantities, such, for example, as gallons, the meter A is provided with an indicator E of any preferred type, so as to en-

able the user to ascertain the quantity of liquid discharged from the machine.

The discharge valve D is combined with a valve-actuating mechanism that comprises a bell crank lever 1 pivotally connected at 2 to a stationary arm 3 on the casing 4 of the valve D, an actuating device F for said lever, preferably a star wheel or rotatable element provided with a plurality of cams 5 that co-operate with a roller 6 on the free end of the lever 1 to move said lever upwardly, so as to open the valve D and a coiled compression spring 7 arranged between the upper side of the lever 1 and the base portion 8 of the meter A for moving said lever in a direction to close the valve D. Any suitable type of valve D may be used, but we prefer to use a plunger valve whose stem 9 is pivotally connected to the lower end of the short arm of the lever 1. The star wheel F is combined with a means (hereinafter described) that normally exerts pressure on same in a direction tending to cause said star wheel to turn forwardly, or to the left, looking at Fig. 1, and a locking pawl 10 is provided for locking said star wheel so as to hold the discharge valve in its closed position; said locking pawl 10 co-operating either directly with the star wheel or with a disk 11 arranged at one side of same and secured thereto and provided in its periphery with a plurality of notches 11^a, any one of which is capable of acting as a stop that co-operates with the locking pawl 10. A manually-operable tripping mechanism is provided for tripping the locking pawl 10, so as to release the star wheel F, and a coin-controlled device is provided for normally locking said tripping mechanism or holding it in an inoperative condition.

In the form of our invention herein shown the tripping mechanism just referred to comprises a manually-operable plunger G reciprocatingly mounted in stationary guides 12 and provided at its inner end with a spring pressed, pivotally mounted pawl 13 whose tooth normally lies in a notch 14 formed in the periphery of a tripping disk H, as shown in Fig. 1, said plunger G being acted upon by a spring 15 that normally holds said plunger in its forward position, as shown in Fig. 1. The tripping disk H is rotatably mounted on a horizontally-disposed rock shaft 16 to which the locking pawl 10 is rigidly connected, and a spring 17 is combined with said disk in such a manner that it constantly exerts pressure on same, tending to cause said disk to turn forwardly or in the direction indicated by the arrow x, shown in Fig. 1. The tripping disk H is provided with a hub 18 that has a cut out portion 19, as shown in Fig. 7, and the rock shaft 16 is provided with a rigid collar 20 that carries a pin 21 which extends longitudinally of the shaft 16 and projects

into the cut out portion 19 in the tripping disk, as shown in Fig. 6. Said rock shaft 16 is journaled in a sleeve 22 or tubular-shaped bearing on a stationary bracket 23, and a spring 24 is combined with said rock shaft 70 so as to exert pressure on same in a direction tending to hold the locking pawl 10 on said shaft in engagement with the notched disk 11 on the star wheel. When the plunger G is moved rearwardly, or toward the right, looking at Fig. 1, the pawl 13 on the rear end of same will rotate the tripping disk H rearwardly until said disk reaches such a position that the pawl 13 passes out of engagement with the notch 14 80 in the periphery of the disk, this rotary movement of the tripping disk storing up energy in the spring 17. As soon as the pawl 13 is disengaged from the tripping disk H in the manner just described, said disk 85 turns forwardly, or to the left, looking at Fig. 1, under the influence of the spring 17, thereby causing the shoulder at one end of the cut out portion 19 in the hub of the disk to strike against the pin 21 on the rigid collar 20 on the rock shaft 16. The sharp blow that said pin 21 receives causes the shaft 16 to turn in opposition to the spring 24, and thus lift the pawl 10 on said shaft out of engagement with the notched disk 11 95 on the star wheel F. As soon as said star wheel is released in this manner it will start to turn forwardly, thereby raising the free end of the lever 1 and causing the valve D to open, the forward movement of the star 100 wheel being arrested, as soon as the valve D is opened by a means which I will herein-after describe.

Any suitable kind of coin-controlled device can be used for locking the tripping 105 plunger G, the coin-controlled device used in the machine herein illustrated consisting of a lever I pivotally mounted on a stationary support and provided at its opposite ends with a locking tooth 25 and a coin 110 holder 26, said lever I being so arranged that the locking tooth 25 engages a notch 25^a in the upper side of the plunger G, when there is no coin in the coin holder 26. The coin holder 26 consists of an open-ended trough or chute on one end of the lever I and provided with a depending spring finger 27 that has a laterally bent portion which acts as a support for the lower edge of a coin that is arranged in the holder 26. When a coin is deposited in the holder 26, the weight of said coin causes the front end of the lever I to rock downwardly, and thus disengage the locking tooth 25 on same from the plunger G, thereby releasing the plunger and permitting it to be forced rearwardly. When said plunger is forced rearwardly an arm 28 that is secured to said plunger and arranged at one side of same strikes against the laterally bent portion of the spring fin- 115 120 125 130

ger 27 on the coin holder and moves said finger 27 rearwardly sufficiently to release the coin and permit it to drop out of the coin holder, thus effecting the discharge of the coin from the coin holder. At the same time energy is being stored up in the means that disengages the locking pawl 10 from the valve actuating device or star wheel F.

The means previously referred to for arresting the forward movement of the valve actuating device F after the valve D has been opened consists of a pawl 29 that we will term a "holding pawl", which coöperates with the notched disk 11 on the star wheel, said holding pawl being shown in broken lines in Figs. 1 and 3. The function of the pawl 29 is to hold the valve D open, and in the form of my invention herein shown said pawl is rigidly secured 20 to a rock shaft 30 that is mounted in a sleeve or tubular-shaped bearing 31 on the bracket 23, said shaft being combined with a spring 32 that exerts pressure on said shaft in a direction tending to force the holding pawl 29 on same in engagement with the periphery of the notched disk 11 on the star wheel. The rock shaft 30 is provided at its outer end with an arm 33 which coöperates with a controlling mechanism 30 governed by the meter A and constructed in such a manner that it causes the pawl 29 to be disengaged from the notched disk 11 on the star wheel after a quantity of liquid equal in value to the value of the coin deposited in the machine has passed the discharge valve D, thereby causing the star wheel or valve actuating device F to turn forwardly sufficiently to permit the spring 7 to force the lever 1 downwardly and close 40 the valve D. The controlling mechanism just referred to comprises a rotatable member J which turns whenever liquid is passing through the meter A, and a hammer or tripping device 34 governed by the member J and arranged in such a manner that it will strike the arm 33 on the holding pawl shaft and disengage the holding pawl 29 from the toothed disk 11 with which it coöperates after a certain quantity of liquid 50 has passed through the meter. In the machine herein shown the controlling member J consists of a disk removably mounted on the hub of a gear 35 that meshes with a pinion 36 on the operating shaft 37 of the meter A, as shown in Fig. 1, said member J being provided at its periphery with a plurality of spaced elements, preferably radially-disposed pins 38 that coöperate with an upwardly-projecting arm 39 on a horizontally-disposed rock shaft 40 which is provided at its opposite end with the hammer 34 that strikes against the arm 33 when the shaft 40 rocks in one direction. The shaft 40 is mounted in a stationary bearing 42,

and a spring 43 is combined with said shaft 65 for turning it in one direction. When the liquid starts to flow through the meter A, the member J starts to turn, and when one of the pins 38 on the periphery of the member J engages the upwardly-projecting arm 70 39 on the rock shaft 40, it causes said shaft to rock and store up energy in the spring 43. After the member J has moved a certain distance, the pin 38 thereon that engages the arm 39 will pass out of engagement with said arm, thus releasing the shaft 40 and causing the spring 43 to throw the hammer 34 forwardly into engagement with the arm 33 on the holding pawl shaft 30, resulting, of course, in the release of the star wheel F. In view of the fact that the member J controls the closing of the discharge valve, it is possible to accurately govern the quantity of liquid discharged from the machine by arranging the pins 38 80 in various positions on the member J. When the pins 38 are arranged comparatively close together, as herein shown, the valve D will remain open for only a short period, and thus discharge a comparatively 90 small quantity of liquid, but by arranging the pins 38 farther apart, the member J will travel a greater distance before the holding pawl 29 is tripped, thus causing the valve D to remain open for a longer period, and 95 consequently, causing the machine to discharge a greater quantity of liquid. In order that the machine may be used advantageously for dispensing gasoline and other liquids whose selling price changes frequently, we have constructed the member J in such a manner that it can be removed easily from the gear 35 and replaced by a controlling member J provided with pins 38 that are arranged differently, or, in other words, 100 spaced farther apart or closer together. This can be effected in various ways, but one simple way of constructing the member J is to provide it with a non-circular-shaped 105 portion 35a on the hub of the gear 35, as shown in Fig. 2.

As previously stated, the star wheel or valve-actuating device F is combined with a means that exerts pressure on same in a 115 direction tending to rotate it forwardly whenever said star wheel is released from the locking pawl 10 and the holding pawl 29. In the machine herein shown a weight 44 is used for effecting the forward movement of the star wheel F, said weight being connected to a cable or other flexible member 45 that is secured to and wound onto a drum 46 which is operatively connected to the star wheel F by means of a pivotally 120 mounted pawl 47 on said star wheel that engages a ratchet wheel 48 on the drum, as shown in Fig. 5. Said star wheel and

drum are rotatably mounted on a horizontally-disposed shaft 49 which is rigidly secured to the bracket 23, as shown in Fig. 6, said drum being provided with a handle 50, shown in Fig. 5, so as to enable the drum to be rotated in a direction to wind the cable 45 onto same. The coöperating pawl and ratchet wheel 47 and 48, respectively, co-operate to cause the drum and star wheel 10 to turn together under the influence of the weight 44 when either the locking pawl 10 or holding pawl 29 are tripped.

If desired, the machine may be constructed in such a manner that it can be operated either by introducing a coin into the machine, as previously described, or by actuating a device that causes the plunger G to be released from the locking lever I. In Fig. 8 of the drawings we have illustrated a machine constructed in this manner, said machine being provided with an electro-magnet 51 arranged in such a manner that when it is energized it will cause the tooth 25 on the lever I to be moved upwardly out of engagement with the plunger G, said electro-magnet being arranged in an electric circuit 52 that is equipped with a controlling switch 53 of any suitable type that can be actuated so as to energize the electro-magnet, and thus render the locking lever I inoperative. The meter, the discharge valve and the various other parts of the machine are arranged in a housing 54, indicated by broken lines in Figs. 1, 3 and 4, so as to prevent anyone from tampering with the mechanism of the machine or operating the discharge valve without introducing a coin into the machine. Said housing is provided with a coin chute 55 arranged in such a manner that the lower end of same will be positioned above the coin holder 26.

To operate the machine it is only necessary to deposit a coin of the proper denomination in the coin chute 55 down which the coin travels into the coin holder 26, the weight of said coin moving the lever I in a direction to release the plunger G. The user then moves the plunger G rearwardly so as to store up energy in the tripping disk H, and as soon as the pawl 13 on the inner end of said plunger passes out of engagement with the disk H, said disk will rotate forwardly and impart a sharp blow to the pin 21 on the rock shaft 16 that carries the locking pawl 10, thereby disengaging said locking pawl from the notched disk 11 on the star wheel F and causing said star wheel to rotate forwardly under the influence of the weight 44. The forward movement of said star wheel causes one of the cams 5 thereon to engage the free end of the lever 1 and move it upwardly or in a direction to move the valve D into its open position. The star wheel F rotates forwardly just far enough to effect the opening of the dis-

charge valve D and the forward movement of said star wheel is then arrested by the holding pawl 29. As soon as the valve D opens, the operating shaft 37 of the meter A will start to rotate, and thus impart rotary movement to the controlling member J. When one of the pins 38 on the periphery of the controlling member J strikes against the arm 39 on the rock shaft 40, said shaft will be rocked in a direction to place the spring 43 under tension, and when said member J reaches a certain position, the arm 39 will be released, thereby causing the spring 43 to impart a quick blow to the hammer 34 which strikes against the arm 33. The arm 33 is connected to the shaft 30 that carries the holding pawl 29; consequently, the blow that said arm 33 receives from the hammer 34 causes the holding pawl 29 to be disengaged from the notched disk 11 on the star wheel, said star wheel starting to rotate forwardly as soon as the holding pawl 29 is tripped, and thus permitting the spring 7 to move the lever I in the opposite direction, so as to close the discharge valve D. As the time that the discharge valve remains open is dependent upon the position of the radially-projecting pins 38 on the controlling member J, and as said member J is connected to the meter A in such a manner that it travels at proportionately the same speed as the operating shaft 37 of the meter, it will be seen that by properly positioning the pins 38 on the member J, the quantity of liquid discharged from the machine can be accurately governed. Moreover, as the member J is so constructed that it can be easily removed from the gear 35 that actuates same, as herein shown, it is a very simple matter to modify the machine when the market price of the commodity being vended changes, by simply substituting a different controlling member J provided with pins 38 that are spaced differently. For example, if the market price of the commodity increases, the controlling member J which is then on the machine can be removed and another controlling member having pins 38 arranged closer together can be substituted for same, thus causing the discharge valve D to close when a quantity of the liquid, equal in value at the prevailing market price to the value of the coin deposited has been discharged from the machine. Likewise, if the market price of the commodity decreases, a controlling member J provided with pins 38 spaced farther apart can be slipped over the hub of the gear 35, thus causing the valve D to remain open for a longer period, and consequently delivering a larger quantity of liquid.

A machine of the construction above described is particularly adapted to be used for vending gasoline and oil at points where it is not profitable to employ an attendant to

control the machine, as the machine is of such simple design and rugged construction that it is not liable to get out of order, and it is so designed that it delivers a quantity of 5 liquid equal in value to the value of the coin that is deposited in the machine, and as previously stated, it is so constructed that it can be modified easily when the market price of the liquid varies, by simply substituting a different controlling member J. The indicator E that is combined with the meter A of the machine enables the user to ascertain the quantity of liquid that he receives in return for the coin which he deposits 10 in the machine, and said indicator also enables the owner of the machine to ascertain just how much liquid has been discharged by the machine for a certain period, thus reducing the liability of theft by 15 a dishonest employee employed for the purpose of collecting the money that has been deposited in the machine by users. While the machine is particularly adapted for use in places where it is not profitable to keep 20 an employee at the machine constantly, it can also be used advantageously at garages and filling stations, and when used for this purpose, it is preferably provided with an electro-magnet or other device, as shown in 25 Fig. 8, for enabling the plunger G to be actuated without introducing a coin into the machine. Furthermore, while the particular machine herein illustrated is designed to be used for vending gasoline and oil, our invention 30 is not limited to a machine designed for this particular purpose, but, on the contrary, is applicable to practically any kind of vending machine in which the discharge of the commodity being vended is governed 35 by a valve. It is immaterial whether or not the meter or measuring mechanism of the machine is provided with an indicator.

Having thus described our invention, what we claim, and desire to secure by Letters 45 Patent, is:

1. In a vending machine of the character described, a valve for governing the discharge of a commodity being vended, a meter or measuring device for the commodity arranged so that it will start to operate when said valve is opened, a valve actuating mechanism comprising an actuating device that governs the opening and closing of said valve, two locking devices combined with said actuating device, a manually-operable means for tripping one of said locking devices, a controlling mechanism operated by the meter for tripping the other locking device, and means which causes said actuating device to operate whenever either of said locking devices is tripped or rendered inoperative.

2. In a vending machine of the character described, a valve for governing the discharge of the commodity being vended, a

meter or measuring device for the commodity arranged so that it will start to operate when said valve is opened, a valve actuating mechanism comprising an actuating device that governs the opening and closing of said valve, two locking devices combined with said actuating device, a manually-operable means for tripping one of said locking devices, a controlling mechanism operated by the meter for tripping the other locking device, means which causes said actuating device to operate whenever either of said locking devices is tripped or rendered inoperative, and a coin-controlled device that normally locks said manually-operable means. 80

3. In a vending machine of the character described, a discharge valve, a meter for measuring the commodity being vended, an actuating mechanism for said valve comprising an actuating device, a locking device 85 that normally holds said actuating device at rest, a manually-operable means for tripping the locking device so as to cause the valve to open, a holding device that co-operates with said actuating device to maintain 90 the valve in its open position, and a controlling mechanism governed by the meter for tripping said holding device after a certain quantity of the commodity being vended has passed the discharge valve. 95

4. A vending machine of the character described, comprising a valve for governing the discharge of the commodity being vended, a meter for measuring the commodity, an actuating mechanism for said valve comprising a rotatable actuating device provided with a plurality of cams, each of which is capable of governing the opening and closing of said valve, means for rotating said device, a locking element that normally holds said actuating device inoperative, a manually-operable means for tripping said locking element, thereby causing one of the cams on said actuating device to become operative for effecting the opening 100 of the valve, a holding element for arresting the movement of said actuating device so as to cause said cam to maintain the valve in its open position, and a controlling mechanism governed by the meter for tripping said holding element. 105

5. A vending machine of the character described, comprising a valve for governing the discharge of the commodity being vended, a meter for measuring the commodity, an actuating mechanism for said valve comprising a rotatable actuating device provided with a plurality of cams, each of which is capable of governing the opening and closing of said valve, means for rotating 120 said device, a locking element that normally holds said actuating device inoperative, a manually-operable means for tripping said locking element, thereby causing one of the cams on said actuating device to become op- 125

erative for effecting the opening of the valve, a holding element for arresting the movement of said actuating device so as to cause said cam to maintain the valve in its open position, a controlling mechanism governed by the meter for tripping said holding element, and a coin-controlled device for locking said manually-operable means.

6. In a vending machine, a governing ele-

10 ment that controls the discharge of the commodity being vended, a meter or measuring device for said commodity, a rotatable actuating device for said controlling element provided with a plurality of cams, each of 15 which is capable of governing the opening and closing of said element, means that normally exerts pressure on said actuating device in a direction tending to cause it to rotate, a locking device and holding device 20 combined with said actuating device and arranged in such a manner that said actuating device will start to turn and thus effect the opening of said controlling element when said locking device is tripped, a manually- 25 operable means for tripping said locking device, and means governed by the meter for tripping said holding device.

7. In a vending machine of the character described, a valve for governing the discharge of the commodity being vended, a rotatable actuating device for said valve, a notched element combined with said device, a locking pawl and a holding pawl that co-operate with said notched element to hold 35 said valve in its closed position and also in its open position, means for tripping said locking pawl so as to cause said valve to open, and means for tripping said holding pawl so as to cause the valve to close after a 40 certain quantity of the commodity has passed said valve.

8. In a vending machine of the character described, a valve for governing the discharge of the commodity being vended, a lever combined with said valve, a star wheel 45 for moving said lever in one direction, a spring for holding said lever in engagement with said star wheel, a locking device and a holding device that co-operate with notches 50 carried by said star wheel, spring-pressed members for tripping said locking device and holding device, a meter for measuring the commodity being vended, a manually-operable means for actuating one of said tripping members, and means operated by the 55 meter for actuating the other tripping member.

9. In a vending machine of the character described, a valve for governing the discharge of the commodity being vended, a rotatable actuating device, means arranged 60 between said device and valve for moving the valve, a drum combined with said actuating device, a weight connected to a flexible member that is wound onto said drum, a

locking device and a holding device combined with said actuating device, a manually-operable means for tripping said locking device, and means for tripping said holding device after a certain quantity of the commodity being vended has passed the discharge valve.

10. In a vending machine of the character described, a valve for governing the discharge of the commodity being vended, a 75 rotatable actuating device, means arranged between said device and valve for moving the valve, a drum combined with said actuating device, a weight connected to a flexible member that is wound onto said drum, a 80 locking device and a holding device combined with said actuating device, a manually-operable means for tripping said locking device, means for tripping said holding device after a certain quantity of the commodity being vended has passed the discharge valve, and means for enabling said drum to be turned in a direction to wind said flexible member onto same. 85

11. In a vending machine of the character 90 described, a valve for governing the discharge of the commodity being vended, an actuating mechanism for said valve comprising a rotatable actuating device, a locking pawl that co-operates with said device, a 95 tripping means for said locking device comprising a disk and a spring that exerts pressure on said disk in one direction, and a manually-operable plunger provided with a pivotally mounted, spring-pressed pawl that 100 co-operates with a notch in the periphery of said disk to store up energy in the spring combined with the disk.

12. In a vending machine of the character 105 described, a valve for governing the discharge of the commodity being vended, an actuating mechanism for said valve comprising a rotatable actuating device, a locking pawl that co-operates with said device, a 110 tripping means for said locking pawl comprising a disk and a spring that exerts pressure on said disk in one direction, a manually-operable plunger provided with a pivotally-mounted, spring-pressed pawl that 115 co-operates with a notch in the periphery of said disk to store up energy in the spring combined with the disk, and a coin-controlled device that normally locks said plunger.

13. A vending machine for the purpose 120 described, comprising a valve that governs the discharge of the commodity being vended, a lever for operating said valve, a rotatable actuating device provided with cams that are arranged to co-operate with 125 one end of said lever to move the lever in one direction, a notched element on said device, a spring-pressed locking pawl and a spring-pressed holding pawl arranged in engagement with said notched element, a tripping 130

- disk for rendering said locking device inoperative, a spring that exerts pressure on said disk in one direction, a manually-operable plunger combined with said disk for storing up energy in said spring and thereafter releasing the spring so that said disk will actuate said locking device, a meter, and a controlling mechanism operated by said meter for tripping said holding pawl.
14. A vending machine for the purpose described, comprising a valve that governs the discharge of the commodity being vended, a lever for operating said valve, a rotatable actuating device provided with cams that are arranged to coöperate with one end of said lever to move the lever in one direction, a notched element on said device, a spring-pressed locking pawl and a spring-pressed holding pawl arranged in engagement with said notched element, a tripping disk for rendering said locking device inoperative, a spring that exerts pressure on said disk in one direction, a manually-operable plunger combined with said disk for storing up energy in said spring and thereafter releasing the spring so that said disk will actuate said locking de-
- vice, a meter, a controlling mechanism operated by said meter for tripping said holding pawl, a locking means that normally holds said plunger inoperative, and means for rendering said locking means inoperative.
15. A vending machine of the character described, comprising a valve for governing the discharge of the commodity being vended, a meter arranged so that it will start to operate when said valve is opened, an indicator combined with said meter, an actuating mechanism for said valve comprising a rotatable actuating device, a weight that exerts pressure on said actuating device in one direction, a locking pawl and a holding pawl combined with said actuating device, a manually-operable means for tripping said locking pawl, a rotatable disk driven by said meter and provided at its periphery with radially-projecting pins, and means that is adapted to be operated by one of said pins for tripping said holding pawl so as to permit the valve actuating device to close said valve.

THEODORE PETERS.
ALBERT F. SONDERMANN.
